UNITED STATES PATENT OFFICE.

CHARLES E. JOHNSON, OF RIDGEFIELD PARK, NEW JERSEY, ASSIGNOR TO JOHNAYE-DON CORPORATION, OF NEW YORK, N. Y., A CORPORATION OF NEW YORK.

PARALLEL RULER.

Application filed June 4, 1921. Serial No. 474,892.

To all whom it may concern:

Be it known that I, CHARLES E. JOHNSON, a citizen of the United States, and a resident of Ridgefield Park, county of Bergen, and 5 State of New Jersey, have invented new and useful Improvements in Parallel Rulers, of which the following is a specification.

My invention relates to improvements in parallel rulers. The object of the invention 10 is to provide a ruler mounted on a roller which can be easily and cheaply manufactured, but which will yet embody many novel features of use to an ordinary draftsman or person desiring to draw parallel 15 horizontal or vertical lines at any given distance apart. The invention consists of the novel devices hereinafter shown and described.

In the drawings accompanying this specification and which form a part hereof I have shown my improvement in its preferred form, although the same may be departed from in its various details without going beyond the scope of my invention. 20 Referring to the drawings, Fig. 1 is a plan view of the ruler showing its main essentials. In Fig. 2, an end view of the ruler and the roller is shown. Fig. 3 is an enlarged view of one end of the ruler 25 showing in greater detail the index feature. Like numbers in the drawings refer to similar parts throughout.

In my preferred form a single sheet of metal is stamped into a ruler denoted by 30 1, of the shape shown, the edge 2 of which is marked off in inches or other units of measurement. The shape can more readily be seen from Fig. 2. The ruler is provided with a housing 3 with end portions 4. 35 When it is assembled these are bent inward and indentations 5 form the bearings for the shaft of the roller 6. The latter is held in place by these bearings but may rotate freely. It is better to provide a solid 40 roller throughout the length of the ruler as then the latter can be used on any size sheet. I also provide indentations 7 along

the edge of the ruler which by keeping that edge slightly raised above the surface of the paper allow the use of pen and ink 50 without the danger of blotting. Incisions 8 are stamped out of the face and in the rear part of the ruler. A pen or pencil when inserted in the points of these incisions will draw straight vertical lines when 55 the ruler is advanced or withdrawn with rotation of the roller. These cuts may be located at any convenient place, but I have found that the most suitable situation is to locate them as shown in the drawings in 60 Fig. 1, at 3, 6 and 9 inches with spaces of $\frac{1}{4}$ and $\frac{1}{2}$ inches between the points 9, 10 and 11. The location of these cuts will depend upon the particular use to which the 65 ruler is desired to be put.

At one end of my ruler I provide an index feature shown in detail in Fig. 3 adapted to permit the draftsman to space his horizontal lines at any desired distance apart. Graduations 12 are marked on the roller to indicate $\frac{1}{8}$ inch spacings or as desired. A cut 13 with an index finger 14 is made in the housing above the markings just referred to. By watching the index 70 the ruler can be withdrawn or advanced 75 the desired distance. Thus parallel horizontal lines can be drawn at proper and equal distances. The rear end 15 of the ruler is turned upward as shown in Fig. 2 and may serve as a rest for a pen or 80 pencil 16.

What I claim as new and desire to secure by Letters Patent is:

A combination ruler comprising a housing and a flat ruling edge both integral 85 with said housing, and a roller mounted in said housing, said ruler having incisions cut in the flat ruling edge adapted to control the drawing of lines perpendicular to said edge.

In testimony whereof, I have signed my name to this specification.

CHARLES E. JOHNSON.
